UNITED STATES PATENT OFFICE

CHARLES H. CORBISHLEY, OF GLEN ROCK, NEW JERSEY, ASSIGNOR TO NEW YORK
FRENCH RANGE COMPANY, OF NEW YORK, N. Y., A CORPORATION OF NEW YORK

DESIGN FOR A RANGE PLATE

Application filed February 3, 1933. Serial No. 47,098. Term of patent 14 years.

To all whom it may concern:

Be it known that I, CHARLES H. CORBISHLEY, a citizen of the United States, residing at Glen Rock, New Jersey, have invented a new, ornamental, and original Design for Range Plate, of which the following is a specification, reference being had to the accompanying drawing, forming a part thereof and of which:

Fig. 1 is a front elevational view of a range plate showing my new design;

Fig. 2 is a central cross-sectional view of the same.

I claim:

The ornamental design for a range plate, as shown.

CHARLES H. CORBISHLEY.
